G. H. BUGENHAGEN.

LAWN SWING.

APPLICATION FILED DEC. 10, 1919.

1,378,004.

Patented May 17, 1921.

Inventor: G. H. Bugenhagen
By Munro & Co. Attn: J. S.

UNITED STATES PATENT OFFICE.

GEORGE H. BUGENHAGEN, OF MINOT, NORTH DAKOTA.

LAWN-SWING.

1,378,004.

Specification of Letters Patent. Patented May 17, 1921.

Application filed December 10, 1919. Serial No. 343,741.

To all whom it may concern:

Be it known that I, GEORGE H. BUGENHAGEN, a citizen of the United States, and a resident of Minot, in the county of Ward 5 and State of North Dakota, have invented a new and useful Improvement in Lawn-Swings, of which the following is a full, clear, and exact description.

My invention relates to improvements in 10 lawn swings, and it consists in the combinations, constructions and arrangements herein described and claimed:

An object of my invention is to provide an improvement over the devices disclosed 15 in my prior applications, Serial No. 317,199, filed August 13, 1919, and Serial No. 330,278, filed Oct. 13, 1919.

A further object of my present invention is to provide a device in which the capacity 20 of the swing is greatly increased over those forms shown in the prior applications for a swing of the same size.

A further object of my invention is to provide a swing in which children or other 25 occupants of the swing may more easily enter and leave the seats.

A further object of my invention is to provide a device in which the carriage of 30 the swing may obtain any desired height in its oscillatory motion without causing the occupants to be brought into contact with the supporting frame.

A further object of my invention is to provide a device in which the hangers or 35 suspension bars can be placed higher than in the devices set forth in my prior applications for a swing having a frame of a given height.

A further object of my invention is to 40 provide a swing in which all danger of pinching the hands between the working parts is eliminated.

Other objects and advantages will appear 45 in the following specification, and the novel features of the invention will be particularly pointed out in the appended claims.

My invention is illustrated in the accompanying drawings, forming part of this application, in which—

50 The view is a perspective of the swing.

In carrying out my invention, I provide four supporting posts or legs 1, 2, 3, and 4 respectively. These posts or legs are arranged in pairs, as shown, the posts 1 and 55 2 being secured at their tops to one end of the bar 5 and the posts 3 and 4 being secured

to the other end of the bar. Brace members 6 and 7 extend from the posts 3 and 4 respectively to the end of the bar 5 at which the posts 1 and 2 are connected. Similar 60 brace members 8 and 9 extend from the posts 1 and 2 respectively to the opposite end of the bar 5.

The carrier is formed by a pair of parallel side pieces 10 and 11 to which are secured 65 seats 12 and 13, the seats 12 facing in one direction and the seats 13 facing in the opposite direction. The carrier, thus formed, is pivotally suspended at its ends by means of suspension bars 14 and 15 respectively, 70 the former being connected to a cross piece 16 pivoted between the bars 1 and 2 and the latter being connected to a cross piece 17 pivoted between the bars 3 and 4. It will be observed that the pivotal connections 18 75 and 19 of the carrier with the suspension bars are above the parallel members 10. The bar 15 is prolonged as shown at 20 and is pivotally connected with a rod 21 which bears laterally extending foot-rests 22. 80 Midway between each pair of opposed seats is a lever 23 which is pivotally connected at its lower end with the rod 21 and which bears a handle 24 at its upper end.

From the foregoing description of the 85 various parts of the device, the operation thereof may be readily understood. The occupants enter the device from the sides and place their feet on the foot-rests 22; then, grasping the handles 24, they push 90 and pull them alternately, pushing with the feet at the same time that they pull on the handle. This gives the swing an oscillatory movement.

It will be noted that there is no danger 95 in this device of the occupants coming in contact with the frame of the swing. The fact that the seats project laterally beyond the center carriage supports gives to the swing a greater capacity for the same size 100 swing. By placing the pivoted supports 18 above the carriage, the possibility of having the hand pinched is reduced to a minimum, since if the hand should be placed between the hangers and the carriage, there is always room for the hand, no matter how high the swing may go.

Secured to the bottoms of the foot rests 22 are longitudinal slats 25 which prevent small children from falling between the foot 110 rests and thereby being injured. These slats are held to the foot rests by U-bolts 26.

In order to change the speed ratio, holes 27 may be provided at the lower end of the hanger 15 and the bar 21 may be adjustably attached thereto. A guard rail may be provided at one or both ends on the swing, as shown at 28, to prevent children from being struck by the moving swing.

I claim:

1. A lawn swing comprising a plurality of supporting posts arranged in pairs, the posts of each pair converging together and being secured to a connecting bar at their tops, a cross piece pivoted between the supporting posts of each pair, suspension bars rigidly secured at one end to said cross pieces, a carrier comprising a central supporting member provided with an upwardly extending portion at each end, said upwardly extending portions being pivotally connected adjacent their upper edges to said suspension bars to provide a space between the lower end of each of said suspension bars and the adjacent portion of the carrier, laterally extending seats carried by said supporting member on each side thereof, one of said suspension bars being extended below the carrier, and means mounted on the carrier and pivotally and adjustably connected with said extended suspension bar for propelling the swing.
2. A lawn swing comprising a plurality of supporting posts arranged in pairs, each pair of posts converging together and being rigidly secured to a connecting bar at their tops, a cross piece pivoted between the supporting posts of each pair at a spaced distance from their tops, a suspension bar rigidly secured at one end to the middle of each of said cross pieces, and a carrier comprising a pair of parallel sides, each having an upwardly extending portion at each end, the upwardly extending portions at each end of the carrier being arranged to straddle the lower end of each suspension bar and being

pivots connected thereto adjacent the upper edges of said upwardly extending portion to provide a space between the lower end of each of the suspension bars and the adjacent portion of the carrier, a plurality of laterally extending seats secured to each of said sides, a plurality of operating levers disposed between said parallel sides and having a pivotal connection with them, a connecting bar pivotally connected to each of said operating levers at their lower ends, and having a pivotal connection with one of said suspension bars.

3. A lawn swing comprising a plurality of supporting posts arranged in pairs, each pair of posts converging together and being rigidly secured to a connecting bar at their tops, a cross piece pivoted between the supporting posts of each pair at a spaced distance from their tops, a suspension bar rigidly secured at one end to the middle of each of said cross pieces, and a carrier comprising a pair of parallel sides, each having an upwardly extending portion at each end, the upwardly extending portions at each end of the carrier being arranged to straddle the lower end of each suspension bar and being pivotally connected thereto adjacent the upper edges of said upwardly extending portion to provide a space between the lower end of each of the suspension bars and the adjacent portion of the carrier, a plurality of laterally extending seats secured to each of said sides, a plurality of operating levers disposed between said parallel sides and having a pivotal connection with them, a connecting bar pivotally connected to each of said operating levers at their lower ends, and being pivotally and adjustably connected, with one of said suspension bars, and laterally projecting foot rests secured to said operating levers.

GEORGE H. BUGENHAGEN.
